UNITED STATES PATENT OFFICE.

EMIL PUHAKKA, OF HANCOCK, MICHIGAN.

SHOE.

Application filed June 16, 1920. Serial No. 389,375.

To all whom it may concern:

Be it known that I, EMIL PUHAKKA, a citizen of the United States, residing at Hancock, in the county of Houghton and

5 State of Michigan, have invented certain new and useful Improvements in a Shoe, of which the following is a specification.

This invention relates to improvements in shoe structures and has for its principal ob-

10 ject to so construct and assemble the various parts of the shoe as to afford maximum economy in the consumption of leather or other material necessary in the manufacture thereof.

15 A further object is the provision of a shoe of such improved construction as to minimize the time and labor necessary to cut and assemble the parts thereof, the latter operation being of such simple nature as to be 20 accomplished entirely by machinery, thus reducing the expensive item of handling and hand sewing the shoes.

25 A further object is the provision of a shoe wherein the major portion of the upper and toe portions are constructed of a single piece of material, the central portion of the blank from which the parts are constructed being removed and utilized to form the vamp and tongue attaching part in the finished article.

30 With these and other objects in view, the invention consists in certain novel features of construction as hereinafter shown and described and then specifically pointed out in the claims, and in the drawings illustrative 35 of the preferred embodiment of the invention.

Figure 1 represents a perspective view of a shoe constructed in accordance with this invention.

40 Fig. 2 represents a plan view of the relatively small blank constituting the vamp which is cut from the main blank.

Fig. 3 represents a plan view of the reinforce for the heel portion of the shoe.

45 Fig. 4 represents a plan view of the main blank from which the shoe upper and toe portions are formed.

Fig. 5 represents a plan view of the blank forming a part of the shoe upper, and,

50 Fig. 6 represents a plan view of the blank of the shoe tongue.

Referring to the drawing in detail, wherein similar reference numerals designate corresponding parts throughout the

55 several views, the numeral 5 indicates gen-

erally the main blank from which the major portion of the shoe upper is constructed. As is clearly evident by an inspection of Fig. 4, this blank is of substantially rectangular form thus affording extreme economy in cutting the blanks from hide, owing to the number of blanks which may be obtained therefrom. The medial portion of the blank is cut out as indicated at 6 and the cut out portion connects with a slit 7 extending to the edge of the blank and forming the relatively long and short side sections 8 and 9, respectively, of the upper. The corner of the blank diagonally opposite the long side section 8 is curved as at 10 or rounded so that when the material of the blank is curved at the rounded corner 10 the shoe toe 11 is provided, the cut out portion 6 and slit 7 forming a vamp and tongue receiving opening. Subsequent to properly shaping the blank to a desired form, such as suggested in Fig. 1, the meeting edges 11 and 12 of the long and short sections 8 and 9, respectively, are sewed or otherwise permanently secured together at the back of the shoe structure.

An extension 13 is secured to the top edge of the relatively short side section 9 which edge terminates a considerable distance above the ankle of a foot, and this extension is secured along its rear edge to the vertical rear edge 11 of the opposite side section 8, the top edge of the extension 13 lying in the horizontal plane of the top edge of the section 8 to provide a shoe of conventional design. The adjacent front edges of the side sections 8 and 9 and the extension 13 are provided with eyelets or other types of lacing devices 14 whereby the flaps or front edges of the shoe may be secured together in the usual manner.

The cut out portion 6 of the main blank is of such form as to provide the proposed shoulders 15 which, when the blank is properly formed provide the overhanging portions 16 in which several of the lacing eyelets 14 are secured.

The piece of material 17 cut out from the main blank constitutes the blank for the shoe vamp. The flaps or lateral extensions 18 which are formed on the vamp blank 17 by forming the shoulders 15 on the main blank are removed along the lines 19 and likewise the curved or tapered opposite terminal of the blank 17 is cut along the lines 20, a longitudinal slit 21 being formed inwardly from

the end carrying the flaps or side extensions 18 for convenience in inserting the vamp in the cut out portion of the toe.

The vamp thus formed is positioned in the 5 cut out portion of the main blank and is sewed or otherwise secured therein as indicated at 22, the line of stitching being extended inwardly of the overhangs 16 to permit the shoe lace to be conveniently inserted 10 through the eyelets 14.

The tapered tongue piece 23 is stitched or otherwise secured along the dotted lines 24 to the front edges of the side sections 8 and 9 and also to the extension 13, the bottom edge 15 of the tongue piece being secured to the tapered upper extremity of the vamp 17.

A heel reinforcing member 25, the blank of which is illustrated in Fig. 3, is preferably positioned over the heel portion of the 20 shoe to protect the latter against wear and the usual heel and sole 26 and 27 are secured to the shoe upper in any preferred manner. It will be clearly apparent that the shoe construction as hereinbefore described is devoid 25 of any side seams at the heel portion of the upper, excepting at a point above the ankle of the foot, therefore the liability of the bursting of the shoe due to the weakening of seams at the toe or heel portion is eliminated.

What I claim is:

In a high-pace shoe, an upper of a height to extend over the calf of the leg of the wearer and formed of a pair of side portions of unequal length having projecting from the forward termini thereof a continuous seamless toe portion extending inwardly and rearwardly with respect to the front of the shoe and of less width than the forward termini of said side portions, that side portion of shorter length of a length to extend a considerable distance above the ankle of the wearer, an extension secured to the upper edge of and projecting upwardly from that side portion of shorter length and of a length to provide the side portions of a shoe of equal length, a vamp having its lower portion centrally split, said split lower portion of said vamp completely extended against and secured to the inner face of said toe portion and the remaining portion of said vamp extended rearwardly from the toe portion and between and secured to the inner face of the lower part of the side portions, and a tongue secured to the upper end of the vamp and of a length to extend to the top of the side portions.

In testimony whereof, I affix my signature hereto.

EMIL PUHAKKA.
